UNITED STATES PATENT OFFICE

FREDERICK L. BRIGHAM, OF UPPER MONTCLAIR, NEW JERSEY

ELASTIC THREAD AND FABRIC MADE THEREFROM

Application filed December 16, 1930. Serial No. 502,647.

This invention is directed to an improvement in elastic threads and to elastic fabrics made therefrom, and has for one of its objects the provision of an elastic thread 5 possessing certain characteristics as herein-after pointed out which make this improved thread superior to elastic threads as heretofore made.

A further object of my invention is the 10 provision of an improved thread possessing certain characteristics which particularly adapt it for use in knitted elastic fabrics.

In the construction of knitted elastic fabrics as will be understood non-elastic knitting threads are passed about the elastic thread and interlaced with each other, the elastic thread extending lengthwise of the fabric and imparting to the fabric the desired elasticity. In the knitting operation, as above 15 pointed out, the knitting threads are passed about the elastic thread and interlaced with each other, these elastic threads heretofore consisting of a rubber core thread covered with one or more helically applied coverings or wraps of silk or other suitable 20 fibrous material wrapped about the same. Consequently in a finished elastic fabric it will be appreciated that the core of the elastic thread simply lies in channels provided 25 by the coverings of the core thread and that the entire thread in turn simply lies in channels provided by the knitting threads.

It has been found in knitted elastic fabrics, therefore, as heretofore constructed 30 that the elastic thread soon pulls back through the fabric when the fabric is put to use thereby impairing the elasticity and strength of the fabric, the elastic thread imparting the entire resiliency or elasticity to 35 the fabric.

It has been found also that when the elastic fabric is stitched or sewn to a piece of other material care must be exercised that the needle 40 does not cut the core threads of the elastic threads, thereby permitting the core thread to pull out of its covering, thus, as will be appreciated, impairing the strength and elasticity of the fabric. The pulling back of the 45 elastic threads through the channels provided

ed by the knitting threads also strips the coverings from the elastic thread, exposing the core thread to view and thereby effecting the appearance of the fabric.

Another point that must be considered in 55 connection with this prior practice is that in order that the elastic threads may not be cut through when attaching a piece of elastic fabric to a non-elastic, for instance, an attempt is made to skip the elastic threads and 60 this means that fairly long or coarse stitches must be used resulting in a weak joint.

The objections above enumerated are all overcome by the present invention, my invention providing a construction in elastic 65 threads whereby when the thread is incorporated in a knitted elastic fabric in which knitting threads are passed about the elastic thread and interlaced with each other the elastic fabric may be attached to a piece of non-elastic, for instance, by sewing not only through the knitting threads as done heretofore but through the elastic thread as well. This, it will be 70 apparent, enables a strong and neat join to be made between the elastic fabric and non-elastic, insures that the elastic thread will remain in place throughout the life of the fabric and that there can be no pulling back of the elastic thread through 75 the channels of the knitting threads to destroy the elasticity of the fabric nor to strip the covering from the core thread of the elastic thread, thereby exposing the core thread to view and destroying the appearance 80 of the fabric as a wole.

In view of the fact that I am able by the use of my improved thread to stitch the elastic threads in place it will be appreciated as 85 above pointed out that the join between a piece of my fabric and a piece of non-elastic, for instance, will be of maximum strength.

In the drawing:

Fig. 1 is an elevational view of a thread 95 constructed in accordance with my invention;

Fig. 2 is a view in plan on an enlarged scale of a knitted elastic fabric embodying my invention;

Fig. 3 is a section on the line 3—3 of Fig. 2; 100

Fig. 4 is a view similar to Fig. 1 of a modified form of my invention.

Referring to the drawing in detail and first of all to Fig. 1, my improved thread 5 comprises one or more elastic core threads A which may be the same type of material heretofore employed in elastic thread. With this elastic extended to any desired degree, depending upon the degree of elasticity 10 desired in a fabric employing my thread, I apply to the elastic or rubber A a covering B of fibrous material such as silk, cotton or other suitable material. This covering is wrapped helically about the elastic A in a fairly long pitch (somewhat exaggerated in the drawing) so as to leave an appreciable space between the adjacent leads thereof.

I next braid an outer covering E about the 20 thread. This may be done in a continuous operation, or at any convenient time after the application of covering B, it being understood, however, that when braiding the covering E in place the elastic A is under tension, 25 so that the leads of the covering B will be spaced appreciably as above mentioned.

I find that in applying the covering E the 30 wraps or leads of the inner covering B impart somewhat of a corrugated surface to the otherwise smooth exterior of the elastic thread A to prevent slipping of the braided covering with respect to the inner covering B; I find also that the leads of the inner covering B as the outer covering is applied become 35 pressed into the surface of the rubber or elastic A and that the covering E is pinched between the leads of the covering B when the tension in the core thread is released, so that not only is the braided covering E held 40 against slipping with respect to the inner covering B but the inner covering is held against slipping with respect to the elastic A, and the elastic held against slipping with respect to the covering B. 45 In other words, instead of merely two tubes or channels about the elastic, as would be the case if two covers were merely wrapped about the elastic A, as under present practice, I have in effect produced a structure 50 the various elements of which are so bound to each other as to be considered a one-piece thread. As a matter of fact, this result is so pronounced that removal of the coverings B and E from the elastic or the withdrawal of the elastic is very difficult even 55 when deliberately attempted.

It will be appreciated from all of the foregoing that when a piece of my improved fabric is to be sewn to a non-elastic fabric, for instance, the join can be made with much finer stitches than heretofore employed inasmuch as by reason of the improved coverings applied to the core of my improved thread the 60 rubber threads may be sewn through with-

out danger of the core thread slipping back through the fabric or through its covering.

It will be appreciated also that by reason of this fact and by reason of the fact that the rubber core threads are stitched in place the 70 elastic thread cannot slip back through the fabric so that the full strength of the fabric is maintained throughout the life thereof. Not only, therefore, is knitted elastic fabric constructed in accordance with this invention 75 stronger than knitted elastic fabrics as heretofore made, but a join made by using my improved fabric will present a much neater appearance than heretofore possible and the original elasticity of the fabric be available 80 throughout the life of the fabric, as distinguished from prior structures where, as above noted, the elastic threads pull back through the fabric and hence impair its elasticity and its usefulness.

In Figs. 2 and 3 I show my elastic fabric which I have designated G sewn to a non-elastic fabric designated H, the stitches employed in the join being designated J. The knitting threads of these figures of the drawing are designated F and as will be appreciated 85 are passed about the elastic thread of the fabric and interlaced with each other.

While the foregoing description points out the advantages of my improved thread when 90 used in knitted elastic fabrics it is to be understood that the thread also is useful as a warp thread in the woven fabric field as well, where trouble has been experienced with the rubbers of the threads working out of their 95 coverings, a possibility which has been reduced to a minimum by my improved construction.

While I have shown my improved thread 100 as provided with a single covering B immediately about the rubber A, it is to be understood that more than one covering may be employed, if desired, so long as the leads of the coverings are maintained sufficiently 105 spaced to produce the effect above described in connection with maintaining the braided covering in place.

In Fig. 4 the elastic or rubber A' is provided with two coverings B' of fibrous material such as silk, cotton or other suitable material, these coverings being wrapped helically in opposite directions about the elastic A' in a fairly long pitch. As in the case of Fig. 1 I then braid an outer covering E' about 110 the thread so prepared.

What I claim is:—

1. As an article of manufacture a thread 115 comprising an extensible core, a helical covering about said core throughout its entire length, and an outer covering braided over 120 the said core and helical covering.

2. As an article of manufacture a thread 125 comprising an extensible core, a helical fibrous covering for said core so applied as to preserve the elasticity of said core the 130

leads of said covering being disposed in spaced relation, and a covering braided over the helical covering and core.

3. As an article of manufacture a thread comprising an extensible core, a fibrous helical covering about the core throughout the length thereof, and a braided covering immediately about the helical covering and engaging both the core and helical covering.

10 4. A knitted elastic fabric comprising knitting threads passed about extensible threads and interlaced with each other, the extensible threads comprising an elastic core, a fibrous covering helically applied immediately about the core throughout its length and a braided covering immediately about the helical covering and engaged by the knitting threads.

5. In the making of extensible thread, the method which comprises helically wrapping a covering of fibrous material about an elastic core thread throughout its length while the core thread is extended, the said wrapping being so applied as to space the leads thereof from each other and thereafter braiding a covering about the first mentioned covering and the core thread with the core thread extended.

6. As an article of manufacture a thread comprising an elastic core, a helical fibrous covering so applied thereto as to preserve the elasticity of said core, and a fibrous covering braided directly about the first mentioned covering, the first covering being so applied as to space the adjacent leads, some of the material of the second covering being gripped between such leads to maintain the braided covering in place.

This specification signed this 15th day of December, 1930.

FREDERICK L. BRIGHAM.
